UNITED STATES PATENT OFFICE

115,344

DESIGN FOR A FAN SUPPORT

David Chapman, Chicago, Ill.

Application April 10, 1939, Serial No. 84,182

Term of patent 3½ years

To all whom it may concern:

Be it known that I, David Chapman, a citizen of the United States and a resident of Chicago, in the county of Cook and State of Illinois, have invented a new, original, and ornamental Design for a Fan Support, of which the following is a specification, reference being had to the accompanying drawing, forming part thereof.

I claim:

The ornamental design for a fan support, substantially as shown.

DAVID CHAPMAN.
